UNITED STATES PATENT OFFICE

THOMAS HENRY ACASTER, OF OLD TRAFFORD, MANCHESTER, ENGLAND

GOLF TEE

Application filed October 19, 1929, Serial No. 400,938, and in Great Britain December 10, 1928.

This invention comprises an improved form of golf tee which can be conveniently adjusted in height to suit the user's requirements and which will not be readily lost if struck when 5 the ball supported by the tee is played.

Referring to the accompanying sheet of explanatory drawings:—

Figures 1 and 2 are respectively side elevation and plan of a golf tee constructed in accordance with my invention.

The same reference letters in the two views indicate the same parts.

In accordance with my invention, the device comprises a weight or heavy body *a* 15 which is flat so that it will rest upon the ground. Such weight may be made of lead or other heavy material and may be of any desired shape for convenient carriage and manipulation.

20 It is formed with a slot *g* through which projects a thumb-operated sliding member *h* adapted to bear upon the upper side of the ball-supporting member *c* secured to the weight by riveting or otherwise. As *h* is 25 moved to the right along the slot *g*, it lowers the member *c* to a greater or less extent, as shown by the dotted lines in Figure 1, so varying the height of the ball *d* to suit the player's wishes. The ball-supporting end of 30 the member *c* is provided with a cup *i* of leather or other suitable material. A member *b* projects from the weighted body *a* along the ground.

By disposing the tee at a short distance 35 from the weighted body in a known manner, I ensure that if the tee be struck when the ball is played, the projecting member constituting the ball support will revolve about the weight as a pivot but the latter will not be materially moved. The tee will therefore not be lost.

40 I may vary the shape of the weight and projecting members to suit any particular requirements.

What I claim is:—

45 In a golf tee comprising a weighted body with an upper member projecting laterally therefrom upon the end of which the golf ball is supported, such member being adjustable in height to suit the user's requirements, and 50 a second or lower member projecting lateral-

ly to rest upon the ground, a sliding piece within a slot extending across the weighted body for regulating the height of the outer end of the upper projecting member, as set forth.

55 In testimony whereof I have signed my name to this specification.

THOMAS HENRY ACASTER.
